[57] CLAIM

The ornamental design for a holding rack for courier
bags, as shown and described.

DESCRIPTION

FIG. 1 is a front perspective view of a holder for courier
bags embodying any new design according to the
present invention;

FIG. 2 is a front elevational view of the holder of FIG.
1, shown on a reduced scale thereof;

FIG. 3 is an end elevational view thereof, the side oppo-
site being a mirror image of the side shown;

FIG. 4 is a top plan view thereof;

FIG. 5 is a rear elevational view thereof; and,

FIG. 6 is a bottom plan view thereof.

Fig.4.

Fig.5.

Fig.6.
